ELEVATOR

Charles F. Carney, Chicago, Ill., assignor to Westinghouse Electric Elevator Company, Jersey City, N. J., a corporation of Illinois

Application December 21, 1937, Serial No. 180,956

14 Claims. (Cl. 187—29)

My invention relates to elevator systems embodying selector mechanisms and more particularly to floor selector mechanisms that are operated through driving connections with the hoisting apparatus of the cars.

This application is a continuation-in-part of my application Serial No. 132,073, filed March 20, 1937, assigned to Westinghouse Electric Elevator Company, and now abandoned.

10 The floor selectors are provided for connecting the various circuits for the push buttons, floor lanterns, signals, etc. in accordance with the position of the cars. There is a floor selector for each car and it usually comprises a plurality of contact segments arranged in accordance with the positions of the floors and a plurality of cooperating brushes. The brushes are mounted upon a brush arm which is operated to move the brushes over the contact segments in accordance with the movement of the car past the floors it serves. When the brush arm is driven through a direct connection with the hoisting motor or drum, it occasionally gets out of step with the car and fails to correctly engage the contact segments in accordance with the position of the car. That is, when the car is at a floor, the brushes will not be on the contact segments for that floor, but will be off-center and may even be in contact with the contact segments for some other floor. This 20 failure of correct positioning of the brush arm may occur by reason of creepage of the hoisting cables where the car is operated by friction drive or it may at times occur because of stretching of the hoisting cables. When it does occur, the car 25 may fail to stop accurately or to operate its signals correctly and it is necessary to reset the brush arm to avoid trouble.

The main object of my invention is to provide for the automatic resetting of the brush arm of 30 a floor selector whenever it gets out of step with the car, regardless of whether the car is at its terminals or its operating at floors between the terminals.

Another object is to provide a simple and inexpensive resetting means for floor selectors which shall be easy to construct, install, operate, and maintain in operation.

For a better understanding of the invention, reference may be had to the accompanying drawings, in which:

Figure 1 is a diagrammatic representation of an elevator system embodying my invention, the control circuits being drawn in what is known as the "straight-line" style; and

Fig. 2 is a key illustration of the relays embodied in Fig. 1.

The illustration of the relays in Fig. 2 shows them with their coils and contact members disposed in horizontal alignment with their positions in the "straight-line" circuits of Fig. 1 so that the reader may readily determine the position of the coil and the contact members of any relay in the "straight-line" circuit. The relays are named as follows:

K=Non-interference relay	10
U=Up direction switch	
D=Down direction switch	
UP=Up direction preference relay	15
DP=Down direction preference relay	
G=Starting relay	
E=Door relay	
SL=Low-speed line switch	
H=High-speed line switch	
RW=Retardation relay	20
HW=High-speed accelerating relay	
S=Floor stopping relays	
UQ=Up leveling switch	
DQ=Down leveling switch	
UL=Up leveling relay	25
DL=Down leveling relay	
X=Selector correcting relay.	

Although the invention may be utilized in any elevator system embodying a floor selector having a movable arm, it will, for the sake of simplicity, be illustrated and described in connection with a very simple elevator installation such as a low-speed automatic system operated by a single call button at each floor and a single call button for each floor in the car. In this simple system, the elevator car is operated by the passengers pressing the push buttons at the floors to call the car to them. When the car arrives they open the door, enter the car, close the door and then press the button in the car for the floor to which they desire to travel. Then the car will automatically go to and stop at that floor. Also, in this simple system the passenger who first operates the push button for the car has control of the car until he is through with it, and during the time he has the car, the push buttons for the other floors are rendered ineffective so that no other passenger can interrupt the operation of the car.

Referring more particularly to the drawings, I have illustrated an elevator car 10 as supported by a cable 11 passing over a hoisting drum 12 to a suitable counterweight 13. The hoisting drum is mounted upon a shaft 14 disposed to be driven by a high-speed three-phase alternating-current 55

motor HM and a low-speed three-phase alternating-current motor LM. An electromagnetic brake 15 having an energizing coil 16 is provided for controlling the car when it makes a stop, and a speed reducing gear mechanism 18 is provided to permit the use of high-speed motive means in the operation of the hoisting drum 12. The rotors of the high-speed motor and the low-speed motor are mounted on the shaft 14, and their stator or field windings HM¹, HM² and HM³ and LM¹, LM² and LM³ are illustrated in the wiring diagram. The high speed motor is used for starting and running the car at normal high speed. The low speed motor is used after the high speed motor is disconnected for retarding the car and moving it into a floor at a landing speed. Other suitable motive means may be utilized, if desired.

An up direction switch U and a down direction switch D are provided for connecting the motors to a source of electric energy represented by the supply conductors L₁, L₂ and L₃ for operating the car in either the up direction or the down direction. These direction switches are controlled by the push buttons in the car and by the push buttons at the floor landings which the car serves. The car buttons are indicated as BC for the basement floor, 1C for the first floor, 2C for the second floor, and 3C for the third floor. The floor buttons are indicated as 1F for the basement, 1F for the first floor, 2F for the second floor, and 3F for the third floor. It is to be understood that the elevator system may be designed for any suitable number of floors, and that only three floors and the basement are shown in the present illustration for the sake of simplicity.

A plurality of stopping relays are provided for effecting the stopping of the car at a floor when it is answering a call for that floor. The stopping relay for any floor is energized by the pressing of a button for that floor so that it will stay energized until the car comes to and stops at that floor. The stopping relays are indicated as BS for the basement, 1S for the first floor, 2S for the second floor, and 3S for the third floor.

A pair of direction preference relays are provided to be controlled by the floor stopping relays in accordance with the position of the car either above or below the operated floor stopping relay. The up direction preference relay is designated as UP and the down preference relay as DP.

A non-interference relay K is provided to be energized when a push button is pressed by an intending passenger so that no other passenger can secure possession of the car while the first passenger is using it. The relay K is provided with a dash-pot 19 so that it closes its contact members slowly upon being deenergized when the car reaches its destination. This delayed operation of the relay K permits the passenger in control of the car to have sufficient time for opening or closing the door and to enter or leave the car before the next passenger may take over its control.

A starting relay G is provided for conditioning the control system to start the car when one of the push buttons has been operated to move it to a floor.

The car may be provided with a suitable door 20 with which is associated a door relay E for conditioning the control system for operation when the door is closed and for preventing operation of the car while the door is open.

The stator windings of the high-speed motor

are provided with a plurality of resistors r₁, r₃ and r₅ for controlling the acceleration of that motor in starting. The field or stator windings of the low-speed motor are provided with a plurality of resistors r₂, r₄ and r₆ so that the retarding torque of that motor may be increased when it is connected for bringing the car into a floor at a landing speed.

A high-speed accelerating relay HW is provided for short circuiting the resistors r₁, r₃ and r₅ in the circuit of the field windings of the high-speed motors, and a retardation relay RW is provided for short circuiting the resistors r₂, r₄ and r₆ in the circuit of the low-speed motor.

A high-speed line switch H, controlled by the starting switches, is provided for connecting the field winding of the high-speed motor and for operating the high-speed accelerating relay.

A low-speed line switch SL is provided for connecting the field windings of the low-speed motor and for energizing the retardation relay RW. The relays HW and RW are provided with dash-pots 22 and 23 so that they will delay closing their contact members for a predetermined period after being energized, thus delaying the short circuiting of the resistors in the circuits of the field windings for the motors for a predetermined period after the motors start, so that they will be cut out of the circuit at the right time.

An up limit switch ULS and a down limit switch DLS of old and well known construction may be provided for limiting movement of the car when it arrives at either the upper or the lower terminal.

The car is provided with a leveling means for causing it to stop level with the floor for which it has answered a call. The floor leveling means comprises an up leveling relay UL and a down leveling relay DL. The up relay UL is controlled by an up leveling switch UQ and the down relay DL is controlled by a down leveling switch DQ. The up switch UQ is actuated by an up cam U₂₅ and the down switch by a cam D₂₅. A pair of up and down cams should be mounted on the walls of the hatchway (not shown) at each floor. In this installation it will be assumed that the switches are disposed in permanent position on the car and that the low speed of the car permits it to move the switches over the cams every time it passes the floor at which the cams are located. However, if desired, the switches may be so mounted on the car that they may be retracted except when the car is approaching a floor at which a stop is to be made. However, inasmuch as leveling switches and cams of this nature are old and well known in the art, it will be assumed that the elevator engineer will select such leveling switches and cams as he deems advisable.

If the car overruns the floor on a down trip stop, the up leveling switch will be closed to energize the up leveling relay to operate the up direction switch to bring the car back up the hatchway to a position level with the floor. On the other hand, if the car underruns the floor on a down trip stop, the down leveling relay will be energized by the position of the down switch on the down cam to cause the down direction switch to be operated to move the car down level with the floor. Also, the leveling relays are so connected in the control system that they will hold in the correct direction switch as the car approaches a stop until the car reaches the stopping point.

The relays and switches may be provided with

energy from a control circuit represented by the conductors L+4, L-4, L+5 and L-5 connected to the supply conductors L₁, L₂ and L₃ through a suitable rectifier 29. A floor selector FS is provided for connecting the various circuits for the relays, switches, etc., in accordance with the position of the car with reference to the floors it serves. The floor selector comprises a plurality of stationary contact segments disposed on a frame or support 27 for the various floors, a constant supply contact strip 28 and a plurality of cooperating brushes 30, 31 and 32.

The up contact segments disposed under the up brush 30 are for the up stopping relays and are designated as BUA for the basement, 1UA for the first floor, 2UA for the second floor, and 3UA for the third floor. The down contact segments under the down brush 31 are designated as 3DA for the third floor, 2DA for the second floor, 1DA for the first floor, and BDA for the basement. The brush 32 engages the contact strip 28 constantly for providing a constant electrical connection between the brushes 30 and 31 and the supply conductor L-5.

The brushes are illustrated as mounted upon a brush arm 33 operated by a screw-threaded shaft 34. The screw-threaded shaft moves the arm up and down the floor selector, thereby moving the brushes over the faces of the contact segments for the floors in accordance with the operation of the car past the floors. The shaft 34 is operated by a pair of beveled gears 35 and 36 operated by shaft 37 which is connected through a friction clutch 38 to the outer end of the hoisting shaft 14.

At times when the brush arm moves to its uppermost or lowermost position, it may not be exactly in step with the position of the car as the car nears the corresponding terminal. In order to cause the brush arm to reset itself or adjust its position to place it in step with the movement of the car, the lower end of the floor selector is provided with a block 40 and the upper end with a block 41. When the brush arm is out of step with the car and reaches the lower block too soon, the block stops its further progress and thus halts the operation of the shaft 34, the gears 35 and 36 and the shaft 37 by reason of the fact that a friction clutch 38 between the shafts 14 and 37 slips and permits the shaft 37 to remain stationary and not operate with the hoisting drum 12. Likewise, when the brush arm reaches the upper end of the floor selector corresponding to the upper terminal and it is out of step with the car, so that it is moving ahead of the position it should occupy in accordance with the position of the car, the arm will strike the block 41 and that block will stop it and prevent its further upward movement. This again stops the operation of the bevel gears 35 and 36 and the shaft 37. However, the friction clutch 38 slips and permits the shaft 37 to remain stationary while the hoisting drum 12 is rotating. Therefore the car pulls into its terminal and leaves the brush arm in its correct position on the floor selector so that it corresponds accurately with the position of the car. With this arrangement, the position of the brush arm is corrected every time the car goes to a terminal.

In apartment house elevators, however, the car is usually parked at the first floor. This means that the car will be operated usually between the first floor and the upper terminal, but will seldom go to the lower terminal in the basement. Hence, if the brush arm gets ahead of the car going up,

it will probably have its position corrected very quickly by the movement of the car when it reaches the upper terminal. However, if the brush arm gets ahead of the car in the down direction, it may be quite awhile before the car makes a trip to the basement and thus cause the brush arm to have its position corrected. This presents some difficulty in the operation of the car when no attendant is employed to see that the brush arm is always in its correct position for operation.

In order to overcome this difficulty, I have provided a means for causing the car to move to the basement whenever the brush arm gets ahead of the position it should occupy in accordance with the position of the car on a down trip. In practicing my invention, I provide a down correcting contact segment on the floor selector panel and a down correcting brush on the brush arm so disposed that the correcting segment and the correcting brush will not engage when the car stops at the 1st floor with its contact brushes in correct position on their segments, but which will be engaged when the car stops at a floor and the brushes are not on their correct segments but are out of step with the car. The down correcting contact segment is mounted on the down side of the floor selector panel adjacent to the 1st floor position and is designated as XA. Its cooperating correcting brush on the brush arm is designated as 43. If desired, a down resetting contact segment may be provided for each floor and an up correcting segment may be provided for one or more floors in the up direction with a cooperating up correcting brush. However, in practice it will usually be found that a sufficient correcting action will be provided if a correcting contact segment is provided for the down direction on the selector for the floor at which the car parks most of the time. In this case it will be assumed that inasmuch as it is an apartment house elevator, the car will be parked at the first floor most of the time. When the floor selector is so out of step with the car on a down trip that the brush arm is in advance of its correct position, the correcting brush 43 will engage the correcting segment XA and thereby energize the control system to call the car to the basement terminal where the position of the brush arm will be automatically reset.

A better understanding of the invention may be had from an assumed operation of the apparatus illustrated in the drawings.

Assuming that the car is standing at the first floor with its door closed. Inasmuch as the car door 26 is closed, the gate contact members 50 are closed, thereby energizing the door relay E by the following circuit:

L+4, 50, E, L-4, at the lower left-hand corner of Fig. 1. The energization of the door relay prepares the starting switch G for operation. Hence the car is ready to respond to any call. Assuming that an intending passenger at the second floor presses the button 2F to call the car, the pressing of the button causes the car to move up to and stop at the second floor by energizing the stopping relay 2S by the following circuit:

L+5, K1, 51, 3Ca, 2Ca, 1Ca, BCa, 2F, 2S, 53, 3S2, L-5. The energized relay 2S opens its contact members 2S1 and 2S2 and closes its contact members 2S3. The closing of the contact members 2S3 provides a self-holding circuit for the relay. The opening of the contact members 2S2 provides an interlocking of the circuit for the

floor relays which when two or more floor push buttons are pressed simultaneously by waiting passengers, will permit energization of only the floor relay for the highest floor button operated. It 5 is provided because, in apartment houses, several waiting passengers are likely to keep their fingers on the floor push buttons at the same time in the hope of being the first one to get possession of the car after it is released by the one 10 who already has it.

The opening of the contact members **2S1** opens the circuit from the resistor **r7** through contact members **3S1**, **2S1**, contact segment **1UA** and brush **30** to the supply conductor **L-5**. The 15 opening of this circuit causes the energy through the current limiting resistor **r7** to flow through the contact members **DP1** and coil **UP** to the supply conductor **L-5**, thereby energizing the up direction preference relay **UP** to cause the 20 car to move upwardly. The energized relay **UP** closes its contact members **UP1**, **UP3** and **UP4** and opens its contact members **UP2** and **UP5**. The closing of the contact members **UP4** energizes the up direction switch **U** by the following 25 circuit: **L+4**, **D6**, **U**, **DP4**, **UP4**, **G3**, **E3**, **L-4**. The energized up direction switch **U** closes contact members **U1**, **U2**, **U3** and **U4** and opens its contact members **U5** and **U6**. The closing of the 30 contact members **U1** and **U2** prepares the windings of the low-speed motor and the high-speed motor for connection to the supply conductors **L1**, **L2** and **L3**. The closing of the contact members **U4** energizes the non-interference relay **K** by the circuit: **L+4**, **U4**, **K**, **L-4**. The energized 35 relay **K** opens its contact members **K1**, thereby preventing another intending passenger from taking the car away from the passenger who has called it, by preventing energization of any of the other floor stopping relays. The closing of the contact members **U4** also energizes the high-speed line switch **H** by the circuit: **L+4**, **U4**, **E1**, **H**, **G2**, **D4**, **ULS**, **L-4**.

The energized relay **H** closes its contact members **H1**, **H2** and **H3**. The closing of the contact members **H1** and **H2** connects the field windings **HM1**, **HM2** and **HM3** of the high-speed motor to the line conductors **L1**, **L2** and **L3**, thereby starting the high-speed motor **HM**. The closing of the contact members **H3** energizes the high-speed accelerating relay **HW** which, by reason of its dashpot **22**, closes its contact members **HW1** and **HW2** after the expiration of a predetermined delay, thus short circuiting the resistors **r1**, **r3** and **r5** in the field winding circuit of the high-speed motor and thereby causing the motor to speed up and operate the car at its normal high speed.

In the meantime the car has started to leave the first floor, and the down leveling switch relay **DL** is temporarily energized by the switch **DQ** being disposed on the cam, but as the car continues, the switch leaves the cam and again de-energizes the leveling relay **DL**. However, no action has resulted from the energization of the relay **DL** because the circuit for the down switch **D** is open at the contact members **UP5**.

As the car approaches within decelerating distance of the second floor, the up direction switch **UQ** engages the cam **U25** and thereby energizes the up leveling relay **UL** which closes its contact members **UL1**, thereby providing an additional circuit for the up relay **U** to hold that relay until the car gets to a position level with the second floor. As soon as the up leveling switch is operated by the up leveling cam, the brush **30** also 70 engages the contact segment **2UA**, thereby short

circuiting the up direction preference relay **UP** and deenergizing that relay because the current does not flow through it now, but flows through the following circuit: **r7**, **3S1**, **55**, **2UA**, **30**, **32**, **28**, **L-5**. 5

The deenergized relay **UP** opens its contact members **UP3**, thereby deenergizing the starting switch **G**, which in turn closes its contact members **G1** and opens its contact members **G3**, **G4** and **G5**. The opening of the contact members **G4** deenergizes the floor stopping relay **2S** and restores it to its normal condition. The opening of the contact members **G2** deenergizes the high-speed line switch **H** which opens its contact members **H1**, **H2** and **H3**, thus disconnecting the high-speed field windings **HM1**, **HM2** and **HM3** from the supply circuit, thereby deenergizing the high-speed motor **HM**. The opening of the contact members **H3** also deenergizes the high-speed accelerating relay **HW** to restore the resistors **r1**, **r3** and **r5** to the circuit of the field of the high-speed motor ready for future operation. 10 15 20

The deenergization of the starting switch **G** also closes its contact members **G4**, thus energizing the low-speed line switch **SL** to close its contact members **SL1** and **SL2**, thus connecting the field windings **LM1**, **LM2** and **LM3** of the low-speed motor to the supply conductors **L1**, **L2** and **L3**, thereby energizing the low-speed motor **LM** and starting it in operation to decelerate the 25 30 35 car and stop it at the second floor.

The closing of the contact members **SL3** energizes the retardation relay **RW** which closes its contact members **RW1** and **RW2**, thereby short circuiting the resistors **r2**, **r4** and **r6** in the circuit of the field windings **LM1**, **LM2** and **LM3** of the low-speed motor **LM**. This increases the retarding torque of the low-speed motor for decelerating the car to arrive at the second floor landing at landing speed. As the car approaches closely 40 to a position level with the second floor, the up switch **UQ** slides off the up cam **U25**, thereby de-energizing the up direction leveling relay **UL** to stop the car. The deenergized relay **UL** opens its contact members **UL1** in the circuit of the up 45 direction switch **U**, thereby deenergizing that switch which in turn opens its contact members **U1** and **U2** to disconnect the motors from the supply conductors **L1**, **L2** and **L3**, and also opens its contact members **U3**, thus deenergizing the 50 brake coil **16** and applying the brake **15** which stops the car and holds it level with the second floor landing. The deenergized up direction switch **U** also opens its contact members **U4**, thereby deenergizing the non-interference relay **K**, but that relay does not immediately close its contact members **K1** because of the time delay 55 provided by its dashpot **19**. The deenergized switch **U** also, in opening its contact members **U4**, deenergizes the low-speed line switch **L**, which 60 in turn deenergizes the retardation relay **RW**, returning them to their normal condition ready for use the next time the car is to be decelerated to a stop at a floor.

As the car stops at the second floor, the waiting passenger opens the door **20** and enters the car, thereby opening the door and gate contact members **50** and thus deenergizing the door relay **E**. 65

Upon the expiration of the predetermined time 70 of delay for which the dashpot **19** of the relay **K** is designed, that relay closes its contact members **K1** in the circuit for the car operating push buttons, thereby conditioning the car for its next operation. 75

By the foregoing operation it is seen how the car may be called to a floor by a passenger pressing the button at that floor.

- It will be assumed now that the waiting passenger at the second floor enters the car, closes the door and presses the car button **IC** to cause the car to move to and stop at the first floor. The closing of the door closes the door contact members **53**, thereby energizing the door relay **10** to prepare the control system for moving the car when the car button is operated. The pressing of the button **IC** energizes the floor stopping relay **1S** for the first floor by the following circuit: **L+5, K1, 51, 3Ca, 2Ca, 1Cb, 1S, 2S2, 3S2, 53, 15 L-5**. The energized relay **1S** opens its contact members **1S2** and **1S1** and closes contact members **1S3**. The closed contact members **1S3** provide a holding circuit for the coil **1S**, and the opened contact members **1S1** cause the down direction relay **DP** to be energized because it opens the circuit which formerly existed through contact members **1S1**, contact segment **2Da**, brushes **30** and **32**, and contact segment **28** to **L-5**, and causes the current to flow now from **L+5** through **25 resistor r3 and coil DP to L-5**. The energized relay **DP** opens its contact members **DP1** and **DP4** and closes its contact members **DP2, DP3** and **DP5** to cause the car to start to and stop at the first floor. The closing of the **30 contact members DP3** energizes the starting switch **G** to close its contact members **G2, G3, G4** and **G5** and open its contact members **G1**. The closing of the contact members **G5** energizes the down direction switch **D** by the following circuit: **35 L+4, U6, D, UP5, DP5, G5, E3, L-4**. The energized down direction switch **D** thereupon closes its contact members **D1, D2, D3** and **D5** and opens its contact members **D4** and **D6** to start the high-speed motor, release the brake and move the car down to the first floor. The closing of the contact members **D1** and **D2** connects the field windings of the high-speed motor **HM** to the supply conductors **L1, L2** and **L3**. The closing of the contact members **D5** energizes the non-interference relay **K** and the high-speed line switch **H**. The energized relay **K** opens its contact members **K1** in the push button circuit thereby preventing appropriation of the car by other passengers. The energized relay **H** closes its contact members **H1** and **H2**, thereby energizing the field windings **HM1** and **HM2** of the high-speed motor to start the car downwardly. The energized relay **H** also closes its contact members **H3**, thereby energizing the high-speed relay **HW** to close its contact members **HW1** and **HW2** after the time delay caused by the dashpot **22** to short circuit the resistors **r1, r3** and **r5** in the field winding circuit of the high-speed motor so that the motor will operate at its normal high speed in **45 moving the car down to the first floor**. The car now moves toward the first floor and the up leveling switch **UQ** leaves the cam **U25**, thereby deenergizing the leveling relay **UL**. However, this relay had no effect because the **50 contact members DP4** are open in the **U** switch circuit. As the car approaches within stopping distance of the first floor, the down leveling switch **DQ** engages the down cam **D25** for the first floor and **55 thereby energizes the down leveling relay DL**, which closes its contact members **DL1** in an additional circuit for the down direction switch **D**, thereby maintaining that switch in its energized condition. At about the same time, the down **60 brush 31** engages the down contact segment **1DA**, thereby deenergizing the down direction preference relay **DP** to cause the high-speed motor **HM** to stop operating the car and permit the low-speed motor **LM** to take over the operation of the car for the purpose of retarding it and moving it into the first floor at a desirable stopping speed. The deenergized relay **DP** opens its contact members **DP3**, thereby deenergizing the starting switch **G** which in turn opens its contact members **G2** to deenergize the high-speed line switch **H** and **10 close its contact members G1 to energize the low-speed line switch L**. The deenergized switch **H** opens its contact members **H1** and **H2**, thereby deenergizing the field windings **HM1, HM2** and **HM3** of the high-speed motor. The opening of **15 the contact members H3** also deenergizes the high-speed accelerating relay **HW** which restores the resistors of the high speed motor to their normal circuit.
- The energization of the line switch **L** closes its contact members **SL1** and **SL2**, thereby energizing the field windings **LM1, LM2** and **LM3** of the low-speed motor to cause that motor to start in operation and carry the car into the first floor landing at its landing speed. The energized relay **SL** also closes its contact members **SL3**, thereby energizing the retardation relay **RW**, which, after the expiration of the predetermined time delay for which it is set, closes its contact members **RW1** and **RW2**, thus short circuiting the resistors **r2, r4** and **r6** in the field winding circuit of the low-speed motor to increase its retarding torque for decelerating the car to its landing speed.
- The car is now approaching the first floor landing on its downward movement at its stopping speed, and, as it reaches the point where it should be stopped, the down leveling switch **DQ** runs off the down cam **D25** and thereby deenergizes the down leveling relay **DL** which opens its **40 contact members DL1**, thus deenergizing the down direction switch **D** to stop the low-speed motor and apply the brake to stop the car level with the floor. In doing this, the deenergized switch **D** opens its contact members **D1** and **D2** **45** to disconnect the motors from the supply conductors **L1, L2** and **L3** and opens its contact members **D3** to deenergize the brake coil **16** and apply the brake **15** to hold the car at the first floor. The passenger now opens the gate and the door **50** and leaves the car, thus opening the gate and door contact members **50**, thereby deenergizing the door relay **E**. The deenergized relay **D** also opens its contact members **D5**, thereby deenergizing the non-interference relay **K**, and after **55** the expiration of the time delay occasioned by the dashpot **19** on that relay, it closes its contact members **K1** to render the push buttons ready for the next operation of the car.
- However, at this point in the operation, it will **60** be assumed that the floor selector arm **33** and the brushes **30, 31** and **32** thereon are ahead of the position of the car and are out of step with the position of the car at the first floor. Inasmuch as the arm is ahead of and out of step with the position of the floor, the correcting brush **43** engages the correcting contact segment **XA** and thereby energizes the selector correcting relay **X** by the following circuit: **L+5, K1, X, 70 XA, 43, 32, 28, L-5**. The energization of the correcting relay **X** enters a call sending the car to the basement floor where the floor selector arm **33** will be forced against the block **40** and the position of the brush arm is thereby corrected **75**.

to place the floor selector in step with the movements of the car.

The energized relay X closes its contact members X1 thereby energizing the floor stopping relay BS for the basement floor by the following circuit: L-5, K1, 51, X1, BS, 1S2, 2S2, 3S2, L-5. The energized relay BS opens its contact members BS1 and closes its contact members BS2. The closed contact members BS2 provide a self-holding circuit for the relay BS. The open contact members BS1 causes energization of the down direction preference relay D by eliminating the short circuit around that relay. The energized relay DP opens its contact members DP1 and DP4 and closes its contact members DP2, DP3 and DP5. The closing of the contact members DP3 energizes the starting switch G, which in turn closes its contact members G5, thus energizing the down direction switch D to start the car downward. The energized switch D closes its contact members D1 and D2, thereby preparing the hoisting motor field circuits for energization and closes its contact members D3 to release the brake 15. The closed contact members D5 energize the non-interference relay K to open its contact members K1 and prevent operation of the other floor relays while the relay BS is in action. The closing of the contact members D5 also energizes the high-speed line switch H, which closes its contact members H1 and H2 to energize the field windings HM2 and HM3 of the high-speed motor, and closes its contact members H3 to energize the high-speed accelerating relay HW, which in turn, after a predetermined time delay, closes its contact members HW1 and HW2, thereby short circuiting the resistors r1, r3 and r5 in the high-speed motor field windings. The car is now moving downwardly toward the basement at its normal high speed.

As the car leaves the floor, the up leveling switch UQ leaves the up leveling cam U25, but the operation of the leveling relay UL has had no effect on the up direction switch because the contact members DP4 were opened in the circuit for that switch when the down direction preference relay was energized. As the car travels to the basement floor, it reaches the point where it should be decelerated for the stop at the basement floor. At this point the down leveling switch DQ engages the down leveling cam D25 and is thereby operated to energize the down leveling relay DL, which closes its contact members DL1 and a second circuit for the down direction switch D and holds that switch in until the car is level with the basement floor.

When the down leveling switch DQ strikes the cam D25, the down brush 31 engages the down contact segment BDA for the basement and thereby short circuits the down direction preference relay DP, thus deenergizing that relay which opens its contact members DP3, thus deenergizing the starting switch G which in turn opens its contact members G4 to deenergize the basement floor relay BS and opens its contact members G2 to deenergize the high-speed line switch H and closes its contact members G1 to energize the low-speed line switch L. The deenergized switch H opens its contact members H1 and H2, thus deenergizing the field windings for the high-speed motor and also opens its contact members H3 to deenergize the high-speed accelerating switch HW to return the resistors in the high-speed motor field windings to their normal condition. At the same time the energized low-speed

line switch SL closes its contact members SL1 and SL2, thereby energizing the field windings of the low-speed motor LM to take over the operation of the car and run it into the basement floor landing at stopping speed. The energized switch SL also closes its contact members SL3, thereby energizing the retardation relay RW to close its contact members RW1 and RW2 after a predetermined delay, thus short circuiting the resistors r2, r4 and r6 out of the circuit for the field windings of the low-speed motor to increase the retardation torque of that motor.

At this point the car is near the basement floor landing and inasmuch as the selector arm 33 and the brushes thereon are ahead of their correct position with reference to the car, the arm engages the block 40 and inasmuch as the car is still moving, the clutch 36 slips and permits the shaft 37, the gears 38 and 35 and the shaft 34 to stop operation while the car catches up with the position of the selector arm so that the selector arm is now disposed in an accurate position with reference to the position of the car to insure accurate operation of the car in the future until the arm again gets out of its correct position and is reset by engagement with the block 40 at the basement terminal or with the block 41 at the third floor terminal.

As the car reaches its stopping position at the basement floor level, the down direction switch DQ runs off the down direction cam D25 for the basement floor, thereby deenergizing the down leveling switch DL to stop the hoisting motor and apply the brake. The deenergized relay DL opens its contact members DL1, thereby deenergizing the down direction relay D which opens its contact members D1 and D2 to deenergize the low-speed motor and also opens its contact members D3 to deenergize the brake coil, thereby applying the brake 15 to stop and hold the car at the basement floor. The deenergized switch D also opens its contact members D5, thereby deenergizing the non-interference relay K and the low-speed line switch SL, which in turn deenergizes the retardation relay RW to return the resistors for the low-speed field winding to their normal condition. Thus the car is stopped level with the floor with its floor selector in correct position with reference to the position of the car.

By reason of the foregoing description, it will be seen that I have provided a means for causing the position of the car selector arm to be automatically corrected when it gets out of its correct position, even though the car fails to run to its correcting terminal. It will also be apparent that the correcting means may be placed at any floor desired or at all the floors, and that it may be provided for the up direction as well as for the down direction.

Further, it is apparent that the correcting means is rendered ineffective while the car is moving between the floors in normal operation by the opened condition of the contact members K1 of the non-interference relay K, so that no inconvenience will be caused by the correcting means trying to operate while the car is moving.

Although I have illustrated and described only one specific embodiment of the invention, it is obvious that many changes therein and modifications thereof may be made without departing from the spirit and scope of the invention.

I claim as my invention:

1. In an elevator system for operating a car

serving a plurality of floors between terminals, motive means, means connecting the car to the motive means whereby operation of the motive means moves the car past the floors, control means for operating the motive means, a floor selector comprising a plurality of contact segments disposed according to the floors and a cooperating brush, means responsive to operation of the motive means in moving the car for moving the brush over the contact segments in accordance and in step with the movement of the car past the floors so that with the car at any floor the brush will be on the contact segment for that floor, means responsive to the brush being out of step with the car while it is moving into a terminal for correcting the position of the brush so that it will be in step with the car, and means responsive to the brush getting out of step with the car while the car is between terminals for causing the control means to effect the movement of the car to a terminal to correct the position of the brush.

2. In an elevator system for operating a car serving a plurality of floors between terminals, motive means, hoisting means connecting the car and the motive means, control means for causing the motive means and the hoisting means to operate the car past the floors, a floor selector comprising a plurality of contact segments disposed according to the floors and a cooperating brush, means responsive to operation of the motive means in moving the car for moving the brush over the contact segments in accordance and in step with the movement of the car past the floors so that with the car at any floor the brush will be on the contact segment for that floor, call means for each floor for registering calls for the car at that floor, means responsive to the brush getting out of step with the car while it is operating at the floors intermediate the terminals for operating the call registering means for a terminal to move the car to that terminal, and means responsive to movement of the car to the terminal for correcting the position of the brush and placing it in step with the car.

3. In an automatic elevator push-button control system, the combination comprising a car movable past floors between two terminal floors, push-buttons at the floors, call registering means responsive to operation of any one of said push-buttons for causing said car to move to the floor corresponding to the operated button, said means comprising a floor selector in which moving elements cooperate with stationary elements, said moving elements moving normally in accordance with movements of said car; an additional element with said moving elements, and a cooperating stationary element responsive to said additional element moving a different than normal amount as said car moves for operating a call registering means for a terminal floor to cause the car to move to that floor.

4. In an elevator system for operating a car serving a plurality of floors between an upper terminal and a lower terminal, motive means for driving the car, a floor selector for the car comprising a plurality of stationary contact segments for the floors and a cooperating contact brush, means connected to the motive means for driving the contact brush over the contact segments in accordance with the movements of the car for connecting circuits for the car in accordance with the position of the car with reference to the floors, a correcting segment and

a cooperating correcting brush mounted on the floor selector and so displaced with reference to the contact segments and the contact brush that they will not be in contact when the contact brush is correctly engaging a contact segment 5 but will be in contact when the contact brush is not correctly engaging a contact brush while the car is standing at a floor, and means responsive to engagement of the correcting brush with the correcting segment while the car is 10 standing at a floor for causing the position of the contact brush to be corrected to move it into step with the position of the car.

5. In an elevator system for operating a car serving a plurality of floors between terminal floors, motive means, hoisting means connecting the car and the motive means, control means for causing the motive means and the hoisting means to operate the car to serve the floors, a floor selector comprising a plurality of contact segments and a cooperating brush, means for supporting the contact segments in accordance with the floors, an arm for supporting the brush, means responsive to operation of the motive means in moving the car for moving the brush arm to carry the brush over the contact segments in accordance and in step with the movement of the car past the floors so that with the car at any floor the brush will be in a predetermined position for the contact segment for that floor, a correcting segment mounted on the segment-supporting means, a correcting brush mounted on the brush arm in position to engage the correcting segment when the brush arm is 30 out of step with the position of the car, and means responsive to engagement of the correcting brush and the correcting segment for correcting the position of the brush arm to bring it into step with the position of the car.

6. In an elevator system for operating a car serving a plurality of floors between terminal floors, motive means, hoisting means connecting the car and the motor, control means for causing the motive means and the hoisting means to operate the car to serve the floors, a floor selector comprising a plurality of contact segments and a cooperating contact brush, means for supporting the contact segments in accordance with the floors, an arm for supporting the contact brush, means responsive to operation of the motive means in moving the car for moving the brush arm to carry the contact brush over the contact segments in accordance and in step with the movement of the car past the floors so that with the car at any floor the contact brush will 50 be in a predetermined position for the contact segment for that floor, a correcting segment mounted on the segment supporting means, a correcting brush mounted on the brush arm in position to engage the correcting segment when the brush arm is out of step with the position of the car, a call means for a terminal for registering calls for the car at that terminal, means responsive to engagement of the correcting contact segment and the correcting brush for operating 60 the call registering means for the terminal, and means responsive to movement of the car to the terminal for correcting the position of the brush arm to place the contact brush in step with the position of the car.

7. In an elevator system for operating a car serving a plurality of floors between terminal floors, motive means, hoisting means connecting the car and the motive means, control means for causing the motive means and the hoisting 75

- means to operate the car to serve the floors, a floor selector comprising a plurality of contact segments and a cooperating contact brush, means for supporting the contact segments in accordance with the floors, an arm for supporting the contact brush, means responsive to operation of the motive means in moving the car for moving the brush arm to carry the contact brush over the contact segments in accordance and in step with the movement of the car past the floors so that with the car at any floor the contact brush will be in a predetermined position for the contact segment for that floor, a correcting contact segment mounted on the segment supporting means, a correcting brush mounted on the brush arm in position to engage the correcting segment when the brush arm is out of step with the position of the car, a call means for a terminal for registering calls for the car at that terminal, means responsive to engagement of the correcting contact segment and the correcting brush for operating the call registering means for the terminal, means responsive to movement of the car to the terminal for correcting the position of the brush arm to place the contact brush in step with the position of the car, and means responsive to operation of the car for rendering the correcting segment and the correcting brush ineffective to operate the call registering means while the brush arm is moving.
8. In an elevator control system for an elevator car operable past a plurality of floors in which the car is caused to stop at any floor in response to the operation of a push button associated with said floor; means movable in accordance with the position of said car for causing said car to stop accurately at any one of said floors, additional means responsive to said first-named means not moving in accordance with movements of said car for causing an additional movement of said car, and means responsive to said additional movement for realigning the relative position of said first-named means with respect to said car's position.
9. In an elevator system for operating a car serving a plurality of floors between terminal floors, motive means, hoisting means connecting the car and the motive means, control means for causing the motive means and the hoisting means to operate the car to serve the floors, a floor selector comprising a plurality of contact segments and a cooperating brush, means for supporting the contact segments in accordance with the floors, an arm for supporting the brush, means responsive to operation of the motive means in moving the car for moving the brush arm to carry the brush over the contact segments in accordance and in step with the movement of the car past the floors so that with the car at any floor the brush will be in a predetermined position for the contact segment for that floor, a correcting contact segment mounted on the segment-supporting means, a correcting brush mounted on the brush arm in position to engage the correcting segment when the brush arm is out of step with the position of the car, means responsive to engagement of the correcting brush and the correcting segment for correcting the position of the brush arm to bring it into step with the position of the car, and means responsive to operation of the control means to move the car for rendering the correcting segment and correcting brush ineffective while the car is moving.
10. In elevator operating apparatus comprising means to move a car to a succession of landings,

a floor finder subject to getting out of correct adjustment with the car, and means operative by movement of the car to a terminal landing to correct the adjustment of the finder when it is out of adjustment towards said landing, the improvement which comprises a device instrumental in causing the car to be sent to said terminal landing and means controlled by the relative position of the car and finder, when the car is stopped at one selected landing, for actuating said device when the finder is out of adjustment towards said terminal landing.

11. In elevator operating apparatus comprising means to move a car to a succession of landings, a floor finder subject to getting out of correct adjustment with the car, and means operative by movement of the car to a terminal landing to correct the adjustment of the finder when it is out of adjustment towards said landing, the improvement which comprises a circuit establishing a condition requiring the car to be sent to said terminal landing and means controlled by the relative position of the car and finder, when the car is stopped at one selected landing, for actuating said circuit when the finder is out of adjustment towards said terminal landing.

12. In elevator operating apparatus comprising normal switch means to move a car to a succession of landings, a floor finder subject to getting out of adjustment with respect to the car and means operative by movement of the car, in addition to its movements caused by said normal switch means, to correct the adjustment of the finder with respect to the car, means responsive to the car and finder being out of adjustment at a landing to cause said additional movement of the car.

13. In an elevator control system for an elevator car operable past a plurality of floors in which the car is caused to stop at any floor in response to the operation of a push button associated with said floor; means movable in accordance with the position of said car for causing said car to stop accurately at any one of said floors, additional means responsive to said first-named means not moving in accordance with movements of said car for causing an additional movement of said car, and means responsive to said additional movement for realigning the relative position of said first-named means with respect to said car's position.

14. In elevator apparatus comprising a car, hoist cables, a traction type hoist drum, a floor finder driven from the drum through a friction drive and having stops preventing its movement beyond stopping position for the respective terminal landings, a main floor between the terminal landings, relays sending the car to the respective landings, electric circuits for energizing the relays for sending the car to the terminal landings, automatic leveling means in addition to said floor finder, a movable contact driven with the floor finder, stationary contacts at the two sides of the position of said movable contact when the car is leveled at the main landing and the floor finder is in correct adjustment, and connections from said contacts which are inoperative while the car is moving and until leveling is completed and are operative after leveling is completed to energize the circuit to the respective relay for sending the car to a terminal landing if said movable contact engages the stationary contact towards said landing.
